METRONOME

Sidney C. Howard, Columbus, and Bert Williams,
Groveport, Ohio

Application December 12, 1939, Serial No. 308,878

1 Claim. (Cl. 58—130)

Our invention relates to improvements in metronomes and the principal object in view is to provide an inexpensive device of this character operative by clock-works and invariable as regards timing so that it may be manufactured as a precision instrument adjusted to beat a set tempo.

To the accomplishment of the above and subordinate objects presently appearing, a preferred embodiment of our invention has been illustrated in the accompanying drawings, set forth in detail in the succeeding description, and defined in the claim appended hereto.

In said drawings:

15 Figure 1 is a view in front elevation of the preferred embodiment of our invention,

Figure 2 is a similar view the cover section of the casing removed,

20 Figure 3 is a fragmentary view in front elevation of the clock-works removed,

Figure 4 is a view in side elevation of the signal carrier and flash plate,

Figure 5 is a view in rear elevation of said carrier and plate, and

25 Figure 6 is a view in edge elevation of the plate.

Referring to the drawings by numerals, the metronome of our invention comprises a flat rectangular casing 1 including a main, open front, back section 2, and a front cover section 3 which 30 may be detachably secured to section 2 in any suitable manner as, for instance, by fitting over the same.

The back section 2 has suitably secured therein, in centered relation thereto, as by screws 4, 35 the frame 5 of a clock-works 6, said frame being arranged upright and the clock-works being of the type embodying an escapement wheel 7 adjacent to the bottom of the frame 5, an escapement controlling fork 8 mounted for vertical oscillation in a fixed bearing sleeve 9 on the frame 5, and a balance wheel 10 coacting with said fork and having attached thereto the usual hair spring, as at 11. The escapement wheel 7 controls the reaction of the usual winding spring 11 through the usual train of gearing designated as a unit, by the numeral 12.

According to our invention, the escapement controlling fork 8 is provided with an integral axis arbor 13 extending through the sleeve bearing 9 and the front of the frame 5, and a right angled upright arm forming an integral extension of said arbor 13 and constituting a signal carrier 14 vibrated between the frame 5 and the cover section 3 under oscillation of the arbor 13. The upper end of the signal carrier 14 has

attached thereto a rectangular, upright flash plate 15 preferably attached to said carrier by means of a rolled edge 16 on the plate sleeved onto and suitably secured to said carrier to be vibrated thereby in a plane parallel with the front face of the cover section 3.

A rectangular sight opening 17 is provided in the front face of the cover section 3 past which the signal plate 15 is vibrated and which is located at either limit of vibratory movement of said plate. The signal plate 15 may be distinctively colored if desired in contrast to the cover section 3 to render the same readily visible to the eye.

At the angle of juncture of the arbor 13 and 15 right angled arm or signal carrier 14 a counter-weight 18 is preferably although not necessarily provided for counterbalancing said carrier and the plate 15.

The operation of the described invention will 20 be readily understood. As the escapement controlling fork 8 oscillates, the arbor 13 is similarly operated to vibrate the signal carrier 14 and the signal plate 15 thereby moving the latter into registration with the sight opening 17 to 25 flash a signal at each stroke of said escapement controlling fork 8. Since the escapement controlling fork 8 is timed as regards oscillation by the hair-spring of the balance wheel 10, the signal flashed by the plate 15 is similarly timed. 30 Thus the timing of the signal is fixed in the device, that is to say, inherent in its structure, so as to indicate, or beat, a constant fixed tempo and such timing cannot be varied without increasing or shortening the length of the hair-spring. By virtue of this arrangement each device may be manufactured to beat a fixed tempo of different timing by varying the length of the hair-spring embodied in the structure. 35

The foregoing will, it is believed, suffice to 40 impart a clear understanding of our invention without further explanation.

Manifestly the invention, as described, is susceptible of modification without departing from the inventive concept and right is herein reserved to such modifications as fall within the scope of the subjoined claim.

What we claim is:

In a device of the class described, a casing having a front wall provided with a sight opening 50 therein, a signal plate adapted to be vibrated in the rear of said opening for intermittent display therethrough, and means to vibrate said plate and to invariably time the vibration thereof comprising a clock-works in said casing includ- 55

ing an oscillating escapement fork having a fixed arbor thereon providing an axis of oscillation therefor, means to invariably time oscillation of said fork, and a plate carrying arm for 5 vibrating said plate forming an integral extension of said arbor whereby vibration of said plate is timed in correspondence with timing of said fork and by said timing means, said arm extending

upwardly at substantially 90 degrees from said arbor, and a counterweight at the juncture of said arbor and arm, said sight opening being disposed at one limit of vibratory movement of said plate. 5
